UNITED STATES PATENT OFFICE.

PERCY WILSON, OF MORRISTOWN, NEW JERSEY.

DESIGN FOR A RADIO CABINET.

Application filed January 26, 1924. Serial No. 8,430. Term of patent 3½ years.

To all whom it may concern:

Be it known that I, Percy Wilson, a citizen of the United States, residing in Morristown, in the county of Morris and State of New Jersey, have invented a new, original, and ornamental Design for a Radio Cabinet, of which the following is a specification, reference being had to the accompanying drawings, forming a part thereof, and of which—

Figure 1 is a front perspective view and Fig. 2 is a side elevation of a radio cabinet showing my new design.

I claim:

The ornamental design for a radio cabinet as shown.

PERCY WILSON.
